UNITED STATES PATENT OFFICE.

LEROY C. DOANE, OF MERIDEN, CONNECTICUT, ASSIGNOR TO THE MILLER COMPANY, OF MERIDEN, CONNECTICUT, A CORPORATION OF CONNECTICUT.

LIGHTING FIXTURE.

Application filed April 23, 1925. Serial No. 25,192.

The present invention relates to lighting fixtures and is more particularly directed toward the provision of a lighting fixture having an extension cord, which is carried outwardly from the canopy of the fixture, and which is suitably supported at a distance from the canopy to permit it to hang free of the parts of the lighting fixture carried below the canopy. Devices of this type are particularly useful in providing convenience outlets for fixtures such as kitchen fixtures.

Fixtures of the type to which the present invention is more particularly directed are sometimes sold without provisions for supporting the extension cord and at other times are provided with such cord supporting devices. It has heretofore been necessary for the manufacturer to make up both types of devices, and for the dealer to carry both types in stock, in order to satisfy the demand of the customers. The devices heretofore available have not been so constructed that one could readily attach or detach the cord supporting device to the canopy of the fixture. According to the present invention there is provided an arrangement of canopy and cord supporting arm which permits the sale of the lighting fixture without the cord supporting arm or with the cord supporting arm, as desired. This permits the dealer and manufacturer to carry a much smaller stock and also makes it easy for one to add a convenience outlet to the fixture where a convenience outlet was not originally installed, or to remove it where it is no longer desired.

The present invention also contemplates an improved device of this type wherein the cord supporting means is entirely independent of the devices which are used in supporting or mounting the lighting fixture on the outlet box or other support. By making these parts independent of one another one is enabled to provide parts each of which is better adapted for its respective purpose, and also the entire fixture may be more easily assembled and installed.

While certain features of the present invention are suited for various type of fixtures the structural embodiment to be described is a kitchen fixture made out of sheet

metal stampings. In this type of fixture it has been found that the cord for the convenience outlet may be readily supported by a wire member suitably bent to shape and so formed that it can be inserted in place in the canopy or removed from it without the use of any attaching device.

The accompanying drawings show for purposes of illustrating the invention one of the many possible embodiments in which it may take form, it being understood that the drawings are merely illustrative of the same, rather than limiting it.

Fig. 1 is a top plan view of a lighting fixture showing the cord supporting arm in position, and

Fig. 2 is a side elevational view of the same with parts in section.

The kitchen unit shown in the drawings includes a canopy 10, a shell 11, a shade or globe 12 carried by the shell, a socket 13, lamp 14, and suitable devices for supporting the unit and carrying the extension cord. One form of device for supporting the unit may be a U-shaped strap 15 whose lower ends are bent outwardly as shown at 16 and 17 and threaded to receive screws 18 and 19. These screws pass through holes in the canopy and nuts 22 and 23 of any desired shape may be threaded into the screws to clamp the canopy on to the strap. The strap is provided with a central hole 24 to receive a crow foot, hickey or gas pipe and with slots 26 and 27 to receive screws for attaching the strap to the lugs of outlet boxes. It will thus be seen that the strap may be attached to any of these devices and the fixture connected thereon as a unit.

As here shown, the canopy and globe supporting shell are sheet metal stampings having flat areas 28 and 29 which are fastened together and which provide a support for the socket 13. While these stampings may be fastened together in various manners, the present invention contemplates fastening them together by a riveting operation in which the material from the globe supporting portion is forced through holes in the canopy and then riveted into the position indicated. In this manner one provides a central hole 29' for the fixture wires and a number of holes 30, which may be

utilized to support the cord carrying arm. The upper edge of the canopy is cut away, as indicated, to provide a narrow slot 31, and an insulating bushing 32 is suitably 5 mounted in the upper part of the canopy near this slot.

The structure so far described may be sold as a complete kitchen fixture. The slot 31 is so narrow that one would not notice it 10 when the fixture is mounted on the ceiling. The fixture is so made that one can readily attach the cord supporting arm, above referred to. This arm is here shown in the form of a piece 33 of bent wire doubled on 15 itself. The ends of the wire are bent downwardly and spread apart as indicated at 34 and 35 so that they may pass through two of the holes 30 and extend a short distance underneath the area 29 of the shade supporting 20 portion of the fixture. The ends of the wire may rest alongside the flat side B' of the socket structure 13, as this economizes in the available space. The wire is extended upwardly as indicated at 36 until it comes to 25 about the level of the bead of the canopy. It is then carried over to the bead and is then bent inwardly as indicated at 37 and 38 to provide shoulders which engage inside 30 the edge of the canopy. These shoulders also narrow the cord supporting member so that it fits inside the notch or slot 31. The cord supporting member then extends laterally from the canopy somewhat as indicated, and is bent downwardly at its outer end, as 35 shown at 39, where it is provided with a cord carrying bushing 40.

A cord 41 for a convenience outlet, a switch or the like, or a combined outlet and switch, may be passed from the inside of the 40 canopy through the bushings 32 and 40. It will hang free from the bushing 40 in the ordinary manner.

The bent wire member 33 may be readily inserted into the canopy by placing the two 45 ends 34 and 35 into the holes 30 bringing the intermediate portion of the member into the notch 31. When the device is mounted on the ceiling, in any of the manners above described, the cord supporting arm 33 is firmly 50 held in place in the notch by the ceiling. The shoulders 37 and 38 prevent pulling the cord supporting member out of the canopy, and by anchoring the inner ends it is impossible to remove the cord supporting member. 55

While the structure shown in the drawings utilizes sheet metal stampings and provides hollow rivets for attaching the inner ends of the cord supporting member it is, of course, obvious that lighting fixtures made of other kinds of material may be provided with a detachable connection which permits the addition of the cord supporting arm to the fixture without tools or other attaching 60 devices.

It is obvious that the invention may be embodied in many forms and constructions and I wish it to be understood that the particular form shown and described is but one of the many forms. Various modifications 70 and changes being possible, I do not in any way limit myself with respect thereto.

I claim:

1. The combination with a lighting fixture having a canopy, a lamp socket, a shade supporting portion, and means for supporting the canopy from the ceiling, of a member whose inner end is releasably connected to the canopy near the center thereof and which passes outwardly over the upper edge of the canopy, and a cord supporting bushing carried by the member. 75

2. The combination with a lighting fixture having a canopy, a lamp socket, a shade supporting portion, and means for supporting the canopy from the ceiling, of a wire member doubled upon itself and having its inner ends releasably attached to the canopy, the member extending laterally from the canopy, and a cord supporting bushing carried in the doubled portion of the wire member. 80

3. In a lighting fixture, in combination, a sheet metal canopy, a sheet metal globe holder, hollow rivets fastening the canopy and globe holder together, and a cord supporting arm whose inner ends are removably carried in the rivet holes, and whose outer end extends beyond the canopy. 85

4. A lighting fixture canopy having two holes carried near the center of the canopy, and a cord supporting arm whose inner end is inserted into the holes, the arm resting on the upper edge of the canopy and extending beyond the canopy, and a cord carrying bushing carried by the outer end of the arm. 90

5. A lighting fixture canopy having two holes carried near the center of the canopy, and a cord supporting arm whose inner end is inserted into the holes, the arm passing through a notch in the upper edge of the canopy, and extending beyond the canopy, and a cord carrying bushing carried by the outer end of the arm, the arm having shoulders inside said canopy to prevent pulling 105 the arm out through said notch. 110

6. A lighting fixture comprising a canopy, a device attachable to a ceiling support and to which the canopy is removably attached, a member carried by the canopy independent 115 of the said device, said member extending laterally from the canopy, an extension cord passing outwardly from the canopy and supported from the end of said member, said member being in the form of a bent piece of wire having ends detachably connected with the canopy and having a shoulder acting against the canopy for holding the member in place. 120

7. A lighting fixture comprising a canopy, 125

a device attachable to a ceiling support and to which the canopy is removably attached, and a wire loop carried by the canopy independent of said device, said loop having a portion extending outwardly from the canopy, said portion being provided with a cord supporting device, said loop extending in-

side the canopy and being releasably locked in place.

Signed at New York city, in the county of New York and State of New York, this 22 day of April, 1925.

LEROY C. DOANE.
